MAGAZINE LOADER FOR AIR GUNS

Andrew Lawrence, New York, N. Y., assignor of
one-half to Stephen E. Laszlo, New York, N. Y.

Application December 3, 1948, Serial No. 63,231

5 Claims. (Cl. 124—48)

1

This invention relates to magazine loaders for air-guns, and provides improvements therein.

The present invention provides a magazine loader for air-guns which holds a plurality of bullets at the breech-end of the gun, from which magazine bullets may be readily fed to the breech of the gun for a succession of discharges. The invention further provides such a magazine loader which is compact and symmetrical; the diameter thereof may be approximately that of the cylinder in which air for discharging the bullet is compressed.

The invention further provides a magazine loader in which bullets are fed to a position in line with the breech-opening from a position around and concentric with the breech opening, and are protected from deformation during the feeding, the magazine loader comprising a plurality of bullet carrying sleeves which envelop and protect the bullets throughout the movements thereof from said position concentric with the breech opening to the position in line with the breech-opening.

The invention also provides a relatively simple and effective mechanism for feeding the bullets and positioning them successively in line with the breech-opening. It further provides a magazine loader which may be combined with the breech-opening and closing mechanism.

One embodiment of the invention is illustrated in the accompanying drawings.

In said drawings,

Figure 1 is a transverse sectional view through the breech-end of an air-gun.

Figure 2 is a rear view of the parts shown in Fig. 1.

Figure 3 is a cross section on the line 3—3, Fig. 1.

Figure 4 is a cross section on the line 4—4, Fig. 1.

Referring to said drawings and particularly to Figure 1, barrel means are therein shown including a cylinder 10 within which air for projecting the bullet is compressed, and within which is arranged a spring pressed piston (not shown); a barrel 12 in the breech-end of which bullet X is held, and through which barrel 12 the bullet is projected by compressed air when the spring pressed piston is released, all of which is well known; and, located at the rear end of the cylinder 10, a breech-piece 14 having a breech-opening 15 therein. The connection to the cylinder may be by screw threads 17. The barrel 12 projects partly into the breech-opening 15, and the breech-opening is of somewhat 55

2

larger diameter than that of the barrel 12, to provide for access of the air compressed in the cylinder 10 to the rear side of a bullet X in position in the breech-end of the barrel. The breech-opening 15 in the breech piece 14 is closed by a breech block 20. The breech block 20 has an opening 21 therein which, in the open position of the breech, registers with the bore of barrel 12.

Threaded on breech-piece 14, as indicated at 10 23, is a cap 22, having a hole 24 therein in line with the breech-opening 15, and through which bullets pass into the breech-opening and into the rear end of the barrel. The breech block 20 is pivoted eccentrically on the breech-piece 14, 15 as by a pin 26. A connection is provided for entraining the breech block 20 with the rotation of cap 22, so that the breech block is moved by the cap to a position to open or close the breech piece to the outside. Such a connection is advantageously provided by a coil or a spring 30, 20 attached at one end to the breech block, as indicated at 31, and having its free convolution bearing frictionally against the inside of the cap 22. Turning of the cap 22 simultaneously turns the 25 breech block 20 on its pivot 26 to close the breech piece by moving opening 21 out of register with barrel 12 and pressing the breech block against the breech-piece 14, or to open the breech by reversing the operation just described.

The mechanism heretofore described may be the same as that described in my application Serial No. 650,771 filed February 28, 1946, now Patent Number 2,525,689.

The magazine loader according to the present invention may be, and preferably is, connected to the barrel means and combined in part with the breech mechanism. That is, the cap 22 may be extended rearwardly and be provided with a cylindrical magazine means 33 for containing a plurality of bullets. The extension 33 is preferably of the same diameter as that of the cap 22. The cap 22, and likewise the cylindrical portion 33, are approximately the same diameter as that of the cylinder 10, and thereby the structure at the breech end of the gun is compact and wieldy. The rear of the cylindrical magazine means 33 of the magazine loader is closed by a rotatable base plate 35. Wing pieces 37, 38 project from the rear of plate 35, and these 40 may be grasped by the fingers and used in rotating the plate 35.

Within the magazine means 33 there is provided a series of pockets 40, surrounding and concentric with the breech-opening 15, each of which is adapted to hold a bullet.

However, the bullets used in air guns usually being relatively soft, being usually made of a lead alloy, it is preferable and desirable to protect the bullets from deformation while in the magazine and while being fed to loading position. For this purpose a plurality of bullet carrying sleeves 45, which are open on both ends, are provided within the magazine and these are positioned directly in the pockets 40, separated by transporting projections 40', bullets X being positioned within and protected by the sleeves 45. The plate 35 has on its inside a segment-shaped projection 47 having a continuous surface 47' on which a plurality of the bullet carrying sleeves 45 rest, and which defines a guide way and a path for the sleeve and holds the sleeves bearing thereon seated within the pockets 40. The plate 35 also has thereon a guiding cam member 50 which engages the bullet carrying sleeves 45 surrounding the breech opening 15 to move them one by one from the concentrically arranged pockets 40 inwardly to a position in line with the breech opening 15. For holding a bullet carrying sleeve in alignment with the breech opening 15, the surface of the guiding member 47 is provided adjacent to the breech opening with a recess 52, and the guiding cam member 50 also has mounted thereon a spring pressed pad 54 which presses a bullet carrying sleeve 45 into the recess 52. A portion 56 of the cam member 50 acts to guide a bullet carrying sleeve 45 from a position in line with the breech opening 15 back into a pocket 40 in the magazine means between two projections 40'. Detent means may be and preferably are provided for stopping and impositively holding the plate 35 in successive positions corresponding to the feeding of a bullet carrying sleeve 45 from a concentric position to a position in line with the breech opening 15. Said means may be conveniently in the form of a spring pressed pin 60 and a series of radial notches 62 in the body of the magazine. Conveniently the notches 62 and also the pockets 40, are formed in an annular member 65 arranged within the cylindrical magazine means 33 of the magazine, and held against movement therein by a press fit. The rotatable plate 35 may be rotatably held within the cylindrical portion 33 of the magazine in suitable manner, as by a split ring 67 fitting within a recess 68 in the cylindrical portion 33.

The rotatable plate 35 is provided with a loading aperture 70, and may also be provided with a central aperture 72 in line with the breech opening 15 through which bullets may be loaded directly into the breech end of the barrel 12. The rotatable plate 35 may also be provided with a series of inspection openings 75 spaced like the pockets 40, and through which the presence or absence of bullets in the bullet carrying sleeves may be observed.

Operation

A bullet X being discharged from the breech end of the barrel 12, the breech cap 22 is turned a part of a revolution to bring the opening 21 in the breech block to a position in line with a breech opening 15, thereby opening the breech, as shown in Fig. 4. The rotation of the cap 22, against the inner side of which the spring 30 attached to the breech 20 presses, acts to turn the breech block on its pivot on the breech piece 14 to and from the breech closing position; and it is to be noted that in turning the breech piece 14 to closing position, the breech cap 22 is drawn

by the threads 23 toward the breech piece 14 and presses the breech block 20 tightly against the breech piece 14.

With the breech open, the plate 35 is turned one step by grasping the wings 37, 38. This one step movement of the magazine plate 35 moves the guiding member 47 one step forward, and also moves the guiding cam member 50 into position to force out of a pocket 40 a bullet carrying sleeve 45 held by a transporting projection 40'; and this movement of the bullet carrying sleeve out of its pocket forces a bullet carrying sleeve ahead of it to move into the pocket 52 in line with the breech opening 15, (and with the opening 21 in the breech block). The spring operated means 54, as heretofore described, holds the bullet carrying sleeve 45 in pocket 52. In this position the gun is pointed downwardly and the bullet in the sleeve in pocket 52 falls downwardly through the opening 21 in the breech block, through the breech opening 15, and into the breech end of the barrel. The bullets X are so made that they will pass into the barrel 12 but will not slide through the same by gravity.

As heretofore described, the stepwise movement of the magazine plate 35 is controlled by the impositive engagement of the spring pressed pin successively in the notches 62.

The breech is then closed by moving the breech cap 22 in the direction opposite to that in which it was moved in opening the breech. This movement of the breech cap turns the breech block 20 on its pivot 26 to a position closing the breech (see dotted lines Fig. 4), and the turning of the breech cap 22, by reason of the threaded engagement with the breech piece 14, also acts to press the breech block 20 tightly against the breech piece 14, as heretofore described. The air gun is now ready for discharge, the discharge being effected by the release of the spring pressed piston within the cylinder 10. The air compressed in the cylinder acts against the rear of the bullet X in the rear end of the barrel 12, and projects the bullet through and from the barrel.

For a second shot, the breech piece 20 is turned to breech opening position, the magazine plate 35 is turned another step, and another bullet carrying sleeve 45 is thereby moved into pocket 52 to position the bullet X therein in line with the breech opening 15 and the opening 21 in the breech block 20, as heretofore described. The sleeve 45 entering pocket 52, forces the empty sleeve in said pocket onto cam 56, and from there into a pocket 40.

The invention may receive other embodiments than that herein specifically illustrated and described.

What is claimed is:

1. In a gun having a barrel means with a breech opening in its rear end arranged coaxially with said barrel means, a magazine loader mounted at the rear end of the barrel means and comprising in combination, guide means including a projection arranged adjacent to said breech opening and having a surface portion serving as a guide way for bullets, a portion of said guide way adjacent to said breech opening being recessed in such manner that a bullet passing along said guide way and abutting against said recessed portion is aligned with said breech opening; spring operated means mounted on said guide means opposite to said recessed portion of said guide way and adapted to urge a bullet passing along said guide way against said recessed portion, and magazine means associated with said guide means

for relative rotation and having at least one transporting projection projecting inwardly towards said guide way and adapted to engage a bullet thereon for moving a row of bullets relative to said guide means along said guide way so that said bullets consecutively reach said breech opening.

2. In a gun having a barrel means with a breech opening at its rear end arranged coaxially with said barrel means, a magazine loader mounted at the rear end of the barrel means and comprising, in combination, guide means including a guiding member located on one side of the breech opening and having a surface portion parallel to the axis of the breech opening and formed with a recess adjacent to the breech opening and shaped in such manner that a bullet located in said recess is aligned with the breech opening, said guide means further including at least one guiding cam member located on the opposite side of the breech opening and having a surface portion facing said surface portion of the inner guiding member whereby between said guiding member and said guiding cam member a bullet path is formed crossing the axis of said breech opening; spring operated means secured to said guiding cam member opposite to said recess for urging a bullet into said recess; and magazine means associated with said guide means for relative rotation and having a plurality of transporting projections adapted to engage bullets located on said bullet path so as to effect movement of the same relative to said guide means along said bullet path to said recess and into alignment with said breech opening whenever a relative movement between said magazine means and said guide means takes place.

3. In a gun having a barrel means with a breech opening at its rear end arranged coaxially with said barrel means, a magazine loader mounted at the rear end of the barrel means and comprising, in combination, magazine means including an annular member provided on its inner surface with a plurality of transporting projections defining pockets; a plurality of bullet carrying sleeves, each bullet carrying sleeve engaged between two adjacent transporting projections; guide means associated with said magazine means for relative rotation and including a guiding member located within said annular member on one side of the breech opening and having a continuous surface portion parallel to the axis of the breech opening and engaging said bullet carrying sleeves and defining a path for the same, said continuous surface portion being formed with a recess adjacent to said breech opening shaped in such manner that a bullet carrying sleeve located in said recess is aligned with the breech opening, said guide means further including a guiding cam member located on the opposite side of the breech opening and having a guiding cam face defining with a corresponding opposite portion of said continuous surface portion of said inner guiding member a guide way for bullet carrying sleeves, said guiding cam member engaging during relative rotation of said guide means and said magazine means bullet carrying sleeves located between two adjacent transporting projections and guiding the same past said recess into a pocket between two adjacent transporting projections; and spring operated means secured to said guiding cam member opposite to said recess and adapted to urge a

bullet carrying sleeve into said recess and into alignment with said breech opening.

4. In a gun having a barrel means with a breech opening at its rear end arranged coaxially with said barrel means and comprising, in combination, magazine means including an annular member provided on its inner surface with a plurality of transporting projections defining pockets; a plurality of bullet carrying sleeves open on both ends, each bullet carrying sleeve engaged between two adjacent transporting projections; guide means associated with said magazine means for relative rotation and including a guiding member located within said annular member on one side of the breech opening and having a continuous surface portion parallel to the axis of the breech opening and engaging said bullet carrying sleeves and defining a path for the same, said continuous surface portion being formed with a recess adjacent to said breech opening shaped in such manner that a bullet carrying sleeve located in said recess is aligned with the breech opening, said guide means further including a guiding cam member located on the opposite side of the breech opening and having a guiding cam face defining with a corresponding opposite portion of said continuous surface portion of said inner guiding member a guide way for bullet carrying sleeves, said guiding cam member engaging during relative rotation of said guide means and said magazine means bullet carrying sleeves located between two adjacent transporting projections and guiding the same past said recess into a pocket between two adjacent transporting projections; spring operated means secured to said guiding cam member opposite to said recess and adapted to urge a bullet carrying sleeve into said recess and into alignment with said breech opening; and a base plate secured to the axis of the breech opening and having a central aperture coaxial with said breech opening, and another aperture adjacent thereto and opening into said path for bullet carrying sleeves and serving for loading bullets into said bullet carrying sleeves, said base plate being further formed with a plurality of spaced openings arranged along said path for bullet carrying sleeves for observing the same.

5. In a gun having a barrel means with a breech opening at its rear end arranged coaxially with said barrel means, a magazine loader mounted at the rear end of the barrel means and comprising, in combination, magazine means including an annular member provided on its inner surface with a plurality of transporting projections defining pockets; a plurality of bullet carrying sleeves, each bullet carrying sleeve engaged between two adjacent transporting projections; guide means associated with said magazine means for relative rotation and including a guiding member located within said annular member on one side of the breech opening and having a continuous surface portion parallel to the axis of the breech opening and engaging said bullet carrying sleeves and defining a path for the same, said continuous surface portion being formed with a recess adjacent to said breech opening shaped in such manner that a bullet carrying sleeve located in said recess is aligned with the breech opening, said guide means further including a guiding cam member located on the opposite side of the breech opening and having a guiding cam face defining with a corresponding opposite portion of said continuous surface portion of said

inner guiding member a guide way for bullet carrying sleeves, said guiding cam member engaging during relative rotation of said guide means and said magazine means bullet carrying sleeves located between two adjacent transporting projections and guiding the same past said recess into a pocket between two adjacent transporting projections; spring operated means secured to said guiding cam member opposite to said recess and adapted to urge a bullet carrying sleeve into said recess and into alignment with said breech opening; and spring operated detent means arranged between said magazine means and said guiding means for holding the same, when rotated relatively to each other, in a plurality of successive positions in which a bullet carrying sleeve is located in said recess. 15
